x Inventor
Peter Budenbach

UNITED STATES PATENT OFFICE.

PETER BUDENBACH, OF NEW YORK, N. Y., ASSIGNOR TO E. R. BENNETT, OF SAME PLACE.

IMPROVEMENT IN COAL-OIL LAMPS FOR LOCOMOTIVES.

Specification forming part of Letters Patent No. **38,001**, dated March 24, 1863.

To all whom it may concern:

Be it known that I, PETER BUDENBACH, of the city, county, and State of New York, have invented a new and improved coal-oil lamp, designed as a head-light for locomotives; and I do hereby declare that the following is a full, clear, and exact description of the same, reference being had to the accompanying drawings, making a part of this specification, in which—

Figure 1 is a vertical section of my invention, taken in the line *x x*, Fig. 3; Fig. 2, a vertical section of the same, taken in the line *y y*, Fig. 3; Fig. 3, a plan or top view of the same.

Similar letters of reference indicate corresponding parts in the several figures.

The object of this invention is to obtain a lamp for burning coal-oil which may be used as a head light for locomotives and operate better than the whale-oil lamps hitherto used, and one which it is believed possesses advantages over the coal-oil lamps hitherto constructed for a similar purpose.

The invention consists, first, in an improved arrangement of the adjustable button for spreading the flame; second, in a horizontal perforated partition-plate placed in the wick-chamber; third, in an improved draft arrangement; and, fourth, in an improved apparatus or device pertaining to the oil-fountain, as hereinafter fully set forth.

To enable those skilled in the art to fully understand and construct my invention, I will proceed to describe it.

A represents a vertical tube, to the lower end of which a perforated cylinder, *B*, is attached by any suitable fastening which will admit of said cylinder being readily attached to and detached from the tube *A*. The cylinder *B* may be made of wire gauze or perforated sheet metal. The latter would probably be preferable. On the upper end of the tube *A* there is fitted a band, *a*, to which the cone or deflector *C* is attached. This cone or deflector may be of the usual shape or form, and it is adjusted higher or lower on the tube *A*, by raising or lowering the band *a*. By this arrangement the cone or deflector may always be adjusted so as to have a proper relative position with the flame of the lamp.

Within the tube *A* there is placed concen-

trically a tube, *D*, which is sufficiently smaller in diameter than *A* to admit of a requisite air-space, *b*, between *A* and *D*, and within the tube *D* there is placed concentrically a tube, *E*, the tube *E* being sufficiently smaller than *D* to admit of a wick-chamber, *b'*, between them, in which a wick-elevator, *F*, is fitted, the latter being the usual sliding tube operated by a rack, *c*, and pinion *d*.

G is a tube, which is fitted within the tube *E*, and is allowed to slide freely up and down within it. This tube *G* has a rod, *H*, secured vertically and centrally in it, said rod having a button, *I*, attached to its upper end. The button *I* may be of the same form as those generally used in lamps of this kind. By this arrangement it will be seen that the button is retained in proper position by the friction of the tube *G* in *E*; but the friction is not designed to be sufficiently great to prevent the free adjustment (raising and lowering) of the button, which is accomplished by grasping the button with the fingers, or by any suitable implement or device. The tube *G*, in consequence of having a good bearing-surface within the tube *E*, prevents the casual movement of the button.

Within the wick-chamber *b* there is permanently secured a horizontal perforated partition, *J*, (shown in Fig. 1.) This partition may be of the same material as the perforated cylinder *B*.

K represents the oil-chamber, which may be described as being a flat box. This oil-chamber is made to communicate with the wick-chamber *b'* by means of an inclined tube, *L*, the lower end of which is below the perforated partition *J* in the wick-chamber. Within the wick-chamber there is placed what may be termed a "bridge," which is constructed of a curved top plate, *c*, both ends of which are in contact with the bottom of the oil chamber. This bridge is not quite equal in width to the oil-chamber, and its front and back sides are formed of perforated plates *d d*. (See Figs. 1 and 2.) Within the bridge, to the under side of its top plate, *c*, there is attached a perforated cylinder, *M*, which extends down to the bottom of the oil-chamber *K* and covers the orifice of the tube *L*. It will be seen that the oil which enters the wick-chamber *b* must necessarily pass through the perforated plates

d d of the bridge, and through the perforated cylinder *M*, and thence down through the inclined tube *L* into the wick-chamber below the perforated partition *J* and up through said partition to the wick. By this arrangement the wick is supplied uniformly with oil as the latter is consumed, the oil being prevented from rising to an undue height in the wick-tube under the unsteady motion of the locomotive. This result is due to the number and arrangement of the perforated plates or surfaces through which the oil is required to pass in order to reach the wick. The top plate, *c*, of the bridge also serves to prevent the commotion or agitation of the oil above it being transmitted to the oil below it. Coal-oil, in order to be burned in lamps of this class, must be prevented from ascending too near the flame, a contingency which frequently happens by the shaking and unsteady movement of the locomotive. My invention fully obviates this difficulty. The perforated cylinder *B* at the bottom of the tube *A*, and extending below it, admits of a uniform supply of air to the flame by a direct and uninterrupted passage or route. The ordinary lamps of this class have their outer tube encompassed by a perforated cylinder, which gives a sinuous passage to the draft—that is to say, a down-

ward and then an upward direction—and this greatly impedes the draft, rendering it fluctuating or variable.

Having thus described my invention, what I claim as new, and desire to secure by Letters Patent, is—

1. Attaching the button *I* to a sliding-tube, *G*, which is fitted within the tube *E*, all arranged, as shown, to support the button in proper position and admit of the ready adjustment of the same, as set forth.

2. The perforated cylinder *B*, attached to the lower end of the outer tube, *A*, of the lamp, when said cylinder is made to project below said tube and form an extension of the same, as and for the purpose set forth.

3. The bridge in the oil-chamber *K*, formed of the curved top plate, *c*, and perforated sides *d d*, and provided with a perforated cylinder, *M*, any one or all of the perforated parts being used, as and for the purpose specified.

4. The perforated partition-plate *J* in the wick-chamber *b'*, as and for the purpose set forth.

PETER BUDENBACH.
